To all whom it may concern:

Be it known that I, John W. Mason, a citizen of the United States, residing at Detroit, in the county of Wayne, State of Michigan, have invented a new, original, and ornamental Design for a Combined Clock and Radio Cabinet, of which the following is a specification, reference being had to the accompanying drawings, forming a part hereof.

Fig. 1 is a front perspective view of a combined clock and radio cabinet, showing my new design;

Fig. 2 is a fragmentary vertical sectional view taken on line 2—2 of Fig. 1;

Fig. 3 is a fragmentary vertical sectional view taken on line 3—3 of Fig. 1; and

Fig. 4 is also a fragmentary vertical sectional view taken on line 4—4 of Fig. 1.

The dominant features of my new design reside in the portion shown by full lines of the drawing.

I claim:

The ornamental design for a combined clock and radio cabinet, as shown and described.
